YARN CONTROL MEANS FOR CIRCULAR
KNITTING MACHINES

James L. Getaz, Maryville, Tenn.

Application May 8, 1937, Serial No. 141,547

18 Claims. (Cl. 66—140)

This invention relates to yarn control means for circular knitting machines, and more particularly to means for clamping yarns fed to cylinder needles. The invention will be described in connection with a revolving needle cylinder machine, but it should be understood that it is not so limited. It is characteristic of the invention that the clamping area is so located and the movement of the yarn fingers out of yarn feeding position is so controlled and timed as to permit entry of the yarn into the clamping area in any desired position, with the result that by using a plurality of clamps the machine can be adjusted to permit different yarns to be put under different clamps, as desired. One of the objects of the invention is to permit selective clamping of different yarns by different clamps, and another object is to permit this to be accomplished within a limited space.

20 In the drawings,

Fig. 1 is a view in elevation from the left side of a circular knitting machine embodying the invention, showing so much as relates to control of the yarn fingers and cutter;

25 Fig. 2 is a plan view taken on the line 2—2 of Fig. 1, showing a portion of the main pattern drum with the heel and toe control of the yarn fingers;

30 Fig. 3 is a development of the cam paths on the auxiliary pattern drum controlling the yarn finger;

35 Fig. 4 is a plan view of the throat plate and clamping mechanism, with the clamping areas arranged in a vertical plane and a yarn being shown entering the clamp;

40 Fig. 5 is a perspective view of the clamps and a yarn finger of Fig. 4, the lower dotted showing of the finger being its feeding position and the solid line its position after starting upward, and the upper dotted showing being its idle position;

45 Figs. 6 and 7 are views in elevation looking outwardly from the center of the machine toward the throat plate, and the cutting and clamping mechanism of Figs. 4 and 5; in Fig. 6 one yarn being shown just before the yarn finger starts to rise from its feeding position; while in Fig. 7 this right hand finger is shown partly elevated with the last needle to take the yarn having moved further to the left as the parts appear in this 50 figure;

55 Fig. 8 is a view in radial section through the throat plate, taken on the line 8—8 of Fig. 6, showing the position of a yarn from a finger which has been moved downwardly into opera-

tive feeding position after its yarn has been cut and clamped;

5 Fig. 9 is a view of the clamping area looking radially inward, the view being taken on the line 9—9 of Fig. 8;

Fig. 10 is a side elevation of the cutter shown in Fig. 5;

10 Fig. 11 is an enlarged detail view in side elevation showing one form of mechanism for moving a yarn finger into and out of operative position;

15 Fig. 12 is an enlarged detail of a modified form of mounting of the yarn finger in which a spring-pressed latch is employed to hold the heel and toe yarn finger in its various positions;

20 Fig. 13 is an elevation looking radially inward at the clamping area, showing how two yarns can be put in different clamps by virtue of the positions of the fingers in the throat plate;

25 Fig. 14 is a view similar to Fig. 13, illustrating how yarns are put under different clamps by changing the time of raising of the fingers;

30 Figs. 15 and 16 are views in side elevation of a modified form of yarn finger particularly suited for this invention; Fig. 15 showing the hinged yarn finger in its retracted or normal feeding position; and Fig. 16 showing the yarn finger in its idle position in solid lines and in its starting feeding position in dotted lines;

35 Figs. 17 to 23 illustrate the invention embodied in a machine where the clamping area lies in a horizontal plane;

40 Fig. 17 is a plan view of a portion of the throat plate and cap, showing three different idled yarns being introduced under three different clamps, one of the yarns being shown a second time after the introduction under the clamps is completed;

45 Fig. 18 is a view in elevation looking outwardly from the center of the machine of Fig. 17, showing how the yarns are introduced under different clamps;

50 Fig. 19 is a detail view in elevation of the cutter of Figs. 17 and 18, the view being taken approximately in a vertical radial plane;

55 Fig. 20 is a view in elevation looking radially outward at the throat plate and clamp of another modification in which two clamps lying in horizontal planes are placed one above the other and selectivity is obtained by proper timing of the raising movement to the yarn fingers;

Fig. 21 is a plan view corresponding to Fig. 20, showing part of the throat plate, yarn fingers, clamps and cutters;

55 Fig. 22 is a view in elevation of the clamps and

needles of Fig. 21, taken on the line 22—22 of Fig. 21; while

Fig. 23 is a detail view showing one of the clamps of Figs. 20, 21 and 22 in end elevation.

In the modern revolving needle circular knitting machine it is desirable to use yarns of different characters and sizes in the fingers in the throat plate and to provide means for clamping a plurality of yarns at the same time. In addition, in the modern circular knitting machine, which often contains wrap stripe fingers and many other parts just inside the needle circle, there is very little room for clamping mechanism for the yarns fed from the throat plate. I have discovered mechanism by which it is possible to hold different throat plate yarns under different clamps and to do this without employing any movable parts in the clamping area. This selectivity and multiple clamping are obtained without the introduction of any parts adjacent the throat plate or clamping area, other than the simplest clamp and cutter, by means of locating the clamps in a specific manner and manipulating the yarn fingers so as to travel through certain specific paths in a special timed relation to the movements of the needle cylinder. It has heretofore been known to utilize the passage of the float of yarn between the yarn finger and the last needle to take the yarn across the needle circle, to place the yarn in a spring clamp lying in a horizontal plane on the top of the dial cap. According to the present invention it is the timed movement of the yarn finger with relation to the last needle to take the yarn that causes the controlled selective clamping.

I will first describe the general features of the machine. The example shown in the drawings is a so-called Standard-Trump revolving needle cylinder machine having the usual needle cylinder 20, upper bedplate 21 and main pattern drum 30 mounted on a vertical axis coaxial with the needle cylinder and just above the main bed 31 of the machine. Mounted at the rear of the machine on a horizontal axis is the auxiliary pattern drum 40 for selecting the yarn fingers in the throat plate during patterning and actuating the cutter for those yarns. Just above the main pattern drum 30 is the horizontal main pattern disk 32 for providing additional control. The control of the cutter and clamp and the yarn fingers except during patterning is from this horizontal pattern disk 32. While no wrap fingers are shown, the embodiment of Figs. 1 to 11 is particularly adapted to machines where the area inside the needle circle is largely taken up by wrap fingers or other mechanism and very little space is available for cutting and clamping mechanism for the yarns fed from the throat plate. In such machines there frequently is only about a quarter of an inch or less just inside the needle circle which is free to be used for such cutting and clamping mechanism. The customary method of cutting and clamping yarns from the throat plate over the shear plate is of course not possible in such machines, and it has heretofore been necessary to mount a clamp and cutter at the throat plate, which makes it necessary to do away with one or more of the yarn fingers usually in the throat plate. In some instances it has been compulsory to reduce the number of yarn fingers from four or five to two in order to accommodate the necessary clamping and cutting mechanism. It will be noted that in my construction the clamp and cutter are so located as to permit the throat plate to be provided with the usual number of

yarn fingers. Referring more particularly to Figs. 4 to 11, the needle cylinder 20 contains the usual independent latch needles 22, and there is the usual latch ring 23. Cut in this latch ring 23 is an opening constituting a throat plate 24. In the example shown in these figures I have illustrated four yarn fingers 25, 26, 27 and 28 in the throat plate, the yarn finger nearest the knocking-over point (i. e., the lowermost finger in Fig. 4) being numbered 25, and the numerals 10 running up as one moves away from the knocking-over point. These yarn fingers are pivoted on an axis 29 located at a level above the throat plate so that when the finger moves from feeding to idle position, the end of the finger swings across 15 the needle circle. The clamping area is located just past the throat plate in the direction of movement of the needles, as can be seen in Fig. 4. There are no moving parts in the clamping area, the clamping means consisting of stationary 20 spring clamps. The clamping means are mounted on the latch ring 23 by means of a bracket 33 extending across the needle circle at a level just above the throat plate and then downwardly in the form of a flat plate 34. The lower end of 25 this plate 34 has a depending tail 35 extending downwardly to approximately the normal level 36 of the needles. This tail 35 is on the edge of the plate nearest the throat plate. This plate 34 lies in a vertical plane just inside the needle circle, 30 the clamps being fastened on its face on the side towards the needle circle, i. e., facing outwardly on the machine. In the example shown in Figs. 4 to 11, there are three clamps 37, 38, 39 fastened at their upper ends and extending downwardly in 35 a vertical direction. The three springs are of 40 different lengths, the longest one being furthest from the throat plate 24 and the shortest one being nearest the throat plate. All three springs are shown as ending above the bottom of the 45 throat plate. The lower ends of these spring-blade clamps are bent slightly outward, as shown in Fig. 8, to facilitate the entry of the yarns under them. In addition the face of the plate 34 on which the clamps lie is corrugated, as shown in Fig. 9, underneath the clamps so as to provide a 50 roughened surface to improve the grip that the clamps have on the yarn.

The bracket carrying the clamps also carries the cutter. In the drawings this cutter is shown as being of the scissors type, with downwardly depending blades. There is a stationary blade 41 lying inside but facing towards the needle circle, and a movable blade 42 adapted, when the scissors are open, to lie across the needle circle. When the scissors formed by blades 41 and 42 are open, the needles are down, and when the scissors are closed, the cutter is out of the path of the needles and it is therefore immaterial whether the needles are raised to the level of the cutter or not. The horizontal pattern disk 32 operates the cutter when going on and off the heel, and the auxiliary pattern drum 40 actuates it during patterning. As shown in Figs. 5 and 10, the movable blade 42 is pivoted on the fixed blade 41 at a point intermediate its ends, so that radially inward movement of the upper end of the blade 42 causes the scissors to open, and radially outward movement of the upper end causes them to close. As shown in Figs. 1 and 4, the upper end of the movable blade 42 is pivotally attached to a link 43 whose outer end is pivoted to the upper end of a bent arm 44 mounted on a bracket 45 carried by the latch ring. The major portion of the bent arm 44 is below 75

its pivoting point on the bracket 45, and extending between the bracket 45 and a point on the arm 44 below the pivot point is a tension spring 46 tending to pull the link 43 radially outward, thereby keeping the scissors closed. The bent lower end of this lever 44 overlies a pin extending laterally from the lower arm of a bell crank lever 47 pivoted on the bracket carrying the latch ring. When the lower arm of the bell 10 crank lever swings upwardly, it pushes against the bent end of the lever 44 and causes the scissors 41, 42 to open against the tension of spring 46. The controls from the horizontal disk 32 and the auxiliary pattern drum 40 are independent of each other but come together at this bell crank lever 47. The connections to the auxiliary pattern drum actuate the bell crank lever by contact with the upper arm, while the controls from the horizontal pattern disk 32 15 actuate the bell crank lever by contact with the lower arm. I will first describe the latter. The horizontal pattern disk 32 revolves in unison with the needle cylinder. Projecting upwardly from the upper surface of this disk are a sufficient number of cams to control the cutting of the yarns from the throat plate pattern fingers 25, 26, 27 which relate to body yarn changes as distinguished from horizontal striping or other pattern effects. These cam surfaces 48 on the upper 20 side of the disk 32 come under the lower ends of a thrust rod 49 which extends upwardly through the upper bedplate 21 and has an extension 49a underlying the lower end of the bell crank lever 47. When a cam 48 raises the thrust 25 rod 49, the bell crank lever is tipped and the scissors 41, 42 open. When the thrust rod drops off the cam 48 the scissors close.

Extending laterally from the upper arm of the bell crank lever 47 is a pin lying in a long slot in one end of a horizontal link 50 whose rear end is linked to a long reading lever 51 extending downwardly to the auxiliary pattern drum. This lever and other similar pivoted levers for the yarn fingers are pivoted on a bracket 52 which is an extension of the main bed 31 of the machine. The notch 53 in which the pin on the upper arm of the bell crank lever lies is long enough so that the bell crank lever can be tipped by the thrust rod 49 without moving the link 50, but when the bell crank lever has not been tipped by the thrust rod 49, the pin lies at the front of the slot 53, so that any rearward movement of the link 50 can tip the bell crank lever. At the lower end of the long reading lever 51 is a reading finger 54 lying in one of the cam paths on the auxiliary pattern drum 40. In this cam path are a suitable number of cams 55 to actuate the cutter whenever any yarn at the throat plate is taken out of action. These cams 55 can be seen in Fig. 3, where the finger 54 is shown up on one of the cams, at which moment the bell crank lever 47 is tipped and the scissors are open, ready to receive a yarn to be cut. As soon as this reading finger 54 falls off the cam 55, the yarn will be cut. The auxiliary pattern drum can be racked forward by pawl 57 acting on teeth 56 on the drum, by any desired mechanism. One suitable means would be to connect the pawl to some element which has a cycle equal to one revolution of the needle cylinder, so that the pattern drum will be racked forward once for each revolution of the needle cylinder. The auxiliary pattern drum turns in the direction of the curved arrow on it in Fig. 1. With this arrangement the cams shown in Fig. 1 will cause the

cutter to be actuated about once every twelve or sixteen revolutions of the needle cylinder. These cams are so placed as to effect cutting for any desired striped pattern. There is a tension spring 58 between the upper bedplate 21 and the upper end of the pivoted reading lever 51 tending to hold the reading cam 54 against the surface of the auxiliary pattern drum 40 and also holding the link 50 in its forward position.

Any ordinary means of raising and lowering the yarn fingers 25, 26, 27 can be employed, but in the drawings, Figs. 1 to 11, I have shown them controlled for patterning purposes from the auxiliary pattern drum 40. The elements immediately associated with the yarn fingers 25, 26, 27 for moving them are very similar to those shown and described in the H. E. Houseman patent No. 1,161,677, dated November 23, 1915. The hub of each yarn finger has teeth 59 in it. These teeth engage similar ones on the hub of a toothed lever 60 pivoted at 61 just in back of the pivot point of the yarn fingers, this lever 60 depending downwardly from its pivot point. The lower end of each lever extends between the arms of a forked bar 62 pivotally supported at its lower end in 25 any desired manner. There is a tension spring 63 tending to pull the forked bar 62 radially outward, which would have the effect of tending to raise the corresponding yarn finger to idle position. Opposed to this tension spring 63 are 30 the elements connecting the forked bar 62 with the auxiliary pattern drum, as shown in Fig. 1. These elements for each yarn finger comprise a horizontal push rod 64 whose outer end is linked to a long pivoted reading lever 65 with a reading 35 cam 66 near the lower end thereof lying against the auxiliary pattern drum 40 and adapted to read the cams 67, 68, 69 in the paths on that drum. There is a tension spring 68 tending to pull the upper end of that lever 65 forward, 40 which would have the effect of pushing the yarn finger down into its operative position. This would be the normal position of the parts, and they leave that position only when a cam on the auxiliary pattern drum tips the lever 65 or some 45 other lever or cam moves the lever 65. As in the case of the cutter, the cams on the auxiliary pattern drum are for the purpose of changing the throat plate yarn for the making of horizontal stripes or the like, and other mechanism is employed for changing the throat plate yarn for the heel and toe or the like. Two other yarn controls are employed for the throat plate yarns. For changes in the body yarn additional thrust rods 48 (not shown), actuated by additional cams 55 on the horizontal pattern disk 32, are employed to throw the yarns into and out of action, the 50 yarn being thrown into action when the thrust rod is raised by any desired connection with the forked arms 62. During the reciprocating knitting of the heel and toe, all the pattern yarn fingers are pulled out of action by means of a cam 69 on the main pattern drum 30. This drum cam moves a reading finger 70 on a pivoted lever 71 adjacent the main pattern drum. This pivoted lever 71 is linked to a rocker arm 73 on the bed of the machine, and there is a pin 74 in the lower end of the rocker arm lying beside the lower ends of the pivoted reading levers 65. These parts are arranged in such manner that when 70 the finger 70 rides up on the drum cam 69, the long levers 65 are rocked, pulling the push rods 64 away from their forked arms 62 and permitting the tension springs 63 to raise the yarn fingers out of operative position.

In the case of the heel and toe yarn fingers, the usual spring-actuated pawl lever 75 can be provided to hold the finger in its up or down position (Fig. 12). The pawl engages either one of the two notches or detents 76 in the hub of the yarn finger, dependent upon whether the finger is swung up or down.

With the construction described above, when a throat plate yarn ceases to be fed to the needles by the yarn finger being raised, the finger motion has as its principal component a vertical movement. The continued rotation of the last needle to take the yarn and the fact that the feeding end of the yarn finger at once crosses the needle circle toward the inside, causes a comparatively small but necessary horizontal component of movement. In this way the portion of yarn between the last needle to take it and the yarn finger—and which length of yarn is under tension—is carried inward and placed accurately against the plate 34 where the clamps are located. As the motion of both ends of this part of the yarn is under positive control, yarn may be placed with precision wherever it is desired. The position of the yarn just before the vertical component of movement carries it upwardly under the clamps is shown in Figs. 4 and 5. The arrow in the lower portion of each figure indicates the direction of movement of the needles, and the arrow in the upper left portion of Fig. 5 shows the direction of movement of the yarn finger. Referring to Fig. 6, the high needle 77 at the right of the figure has been raised to start taking of the yarn, and the dotted line below the top of this needle (at the right of it) indicates the level of the tops of needles which are not raised but will take the splicing yarn because the feeding has been started. Revolution of the needle cylinder brings the yarn between the needle 79 and the yarn finger 27, to a level where it is above the depending tail 35 of the plate 34 and cannot get behind it. Referring now to Fig. 7, we find that the needle 79 has moved still further to the left and the yarn finger 27 has been raised part way so that the parts are now in the position of Fig. 5, or a fraction of a second later than the position of that figure. The yarn has now ceased to feed to the needles. It now lies against the surface of the plate 34, as shown in Fig. 4, and as the yarn finger moves upwardly to its dotted or idle position of Fig. 7, the yarn gets under the three clamps, the cutter closes and the yarn is cut and clamped. It now lies under the clamps, as shown in Fig. 9.

When the yarn finger 27 is at the intermediate level shown in solid lines in Fig. 7, the yarn is just going under the clamps. It is sometimes desirable to have the finger hesitate a moment at this level to give the last needle to take the yarn an opportunity to move the yarn into the clamp while the yarn is not moving vertically. This insures accurate placing of the yarn in the clamps. The hesitation of the finger can be caused by steps in the drum cams operating the yarn fingers. Such steps have been shown in cams 87 and 97 in Fig. 3. Cam 67 can also be stepped if desired. The raising of the finger from the surface of the drum to the step stops the feeding of the yarn and the position of the foot of the cam therefore is not changed when putting in a step on the cam. The end of the bevel also need not be disturbed.

Figs. 6, 7 and 8 also illustrate how a yarn is brought back into operative relation with the needles. As shown in Figs. 6 and 8, when it is

desired to bring a yarn back into feeding position the yarn finger is merely moved down onto the throat plate when, by virtue of the end of the yarn finger crossing the needle circle to the outside, the yarn lies across the path of the elevated needles, as shown in Fig. 8. As this raised needle goes down under the knitting cams, it takes the yarn from the yarn finger and starts to feed, the yarn under the clamp being pulled out as the needle moves along. It is possible to clamp a number of yarns under these three clamps and to move any one of the yarns desired without disturbing the others.

The angle of the yarn between the last needle and the yarn finger as they present the yarn to the clamps is important and it has been found that the differing distance of the yarn fingers in the throat plate from the clamps creates a slightly different angle for each yarn finger. I therefore propose to vary the time of raising the different yarn fingers to give a uniform angle of presentation of the yarn to the clamp. To accomplish this, I use different angles at the beginning of the drum cams 67, 87 and 97, for example, (as shown in Fig. 3) which causes the three yarn fingers to be raised at different speeds. The steps previously referred to are incorporated in the different angles. Thus the drum cam 67 may cause its yarn finger 25 to be raised rapidly, but the slower bevel at the beginning of drum cam 87 will raise its yarn finger 26 at a slower rate, and the bevel at the beginning of drum cam 97 will raise its yarn finger 27 more slowly than either cams 67 or 87. In this way the raising of the yarn finger to assist in stopping the feeding of the needles can be started at the regular time, but the angle of presentation of the yarn to the clamps can be kept uniform from finger to finger.

By utilizing the vertical movement of the yarn due to the raising of the yarn finger, it is possible to use a stationary clamp which occupies very little room, rather than a clamp which has moving parts and for which there would be no room in the average modern circular knitting machine with pattern or dial elements in the cylinder space.

I will now describe the modification shown in Figs. 13 and 14 which illustrates one form of what I shall term "selective clamping". By this term is meant clamping different yarns under different clamps by presenting the different yarns in the clamping area at different angles. One purpose of having selective clamping is to enable yarns of different sizes and character to be held in an effective manner. Broadly speaking, there are two ways in which this presentation of yarns at different positions can be accomplished. It can be caused by raising the yarn fingers at the same time relatively to the location of the needle cylinder and relying on the difference in distance of the yarn fingers from the clamping area to create the difference in angle; or the time of raising the different yarn fingers can be varied so that the difference in angle is due primarily to the difference in position of the last needle to take the yarn. The first method is illustrated in Fig. 13, and the second in Fig. 14. It might be noted that Figs. 13 and 14, in distinction to Figs. 6 and 7, view the parts looking radially inward with the throat plate shown in dotted outline in order that the other parts may be seen more clearly. The direction of movement of the needles in these two figures is from left to right, as shown by the arrowheads at the lower left

of the figures. In Fig. 13, the yarn fingers 25 and 28 are shown at the intermediate or hesitation level corresponding to the steps in the drum cams, and the finger 28 is also shown in its uppermost or idle position. It will be observed that in Fig. 13 the yarn from finger 25 and the yarn from finger 28 both appear to be going to the same needle 79. This is intended to indicate that both yarn fingers were raised to the intermediate level at the same time relative to the rotation of the needle cylinder, though of course on different revolutions. It will be observed that owing to the fact the two yarn fingers are widely separated in the throat plate, the yarn from finger 28 has contacted the plate 34 below the spring clamp 80 and therefore will go under that clamp, while the yarn from finger 25 is at a higher angle and lies on top of the clamp 80. This yarn from finger 25 therefore will go under clamps 38 and 39, but not under 80, while the yarn from finger 28 will go under all three clamps 80, 38 and 39, as shown by the yarn coming from the finger 28 in its solid line position at the top of the figure. It is possible to have a multiplicity of clamps one on top of the other rather than side by side, and in Figs. 13 and 14 this has been illustrated by the superposition of a short clamp 37 on top of the long clamp 80. Thus the yarn from finger 25 will not only go under clamps 39 and 38, but also under the short clamp 37, and all three clamps could be put on top of each other, doing away with the necessity for having clamps side by side.

In Fig. 14, while the yarn fingers 26 and 27 are shown at the same intermediate level where their yarns first contact the plate 34, it will be observed from the positions of their needles that they were not raised at the same rate. While both yarn fingers started to rise at the same moment, the yarn finger 27 was raised more rapidly and reached the hesitation level when the last needle to take its yarn reached the position 82. As a result its yarn will pass under the long clamp 80. On the other hand, the finger 26 was not raised until later, at which time the last needle to take its yarn had moved further to the position 81 and the yarn, when it contacts the clamping area, finds itself on top of the long clamp 80. In this way, one yarn goes under clamps 80, 38 and 39, while the other goes over clamp 80 and under clamps 39, 38 and 37.

As shown in Fig. 11, it is generally desirable that the toe of the yarn finger be as close as possible to the needle circle, particularly in order that the finger may carry the yarn into contact with the plate 34 as soon as possible after the finger starts to rise. In certain types of machines, however, it is best to feed the heel and toe yarn from the corner of the throat plate, and in order to accomplish this it is necessary that the finger be retracted to the position shown in Fig. 15. In beginning to feed the heel and toe yarn the finger is forward in the position of Fig. 11; or the dotted line position in Fig. 16, so that the needles can take the yarn. In have devised a novel yarn finger which can assume its three positions without any outside aid. To do this the drum cam has two heights (not shown) over and above the hesitation step. The length of the push rod 64 is adjusted so that in the idle position of the finger a high portion of the drum cam is in action. When the lower level of the drum is in action, the yarn finger is in the dotted line position of Fig. 16. When the reading cam 66 is on the surface of the auxiliary drum 40, then the parts 75 are in the position shown in Fig. 15 where the

yarn finger is retracted to feed its yarn over the corner of the throat plate. The novel finger is hinged and made in two pieces: a toe portion 83 and a geared leg 84. The geared leg has teeth on it meshing with the usual toothed lever 60, and the leg has a depending portion to the lower end of which the toe portion 83 is pivoted. The pivot point on the toe portion is a short distance from its rear end, and there is a tension spring 85 between the rear end of the toe portion and the leg tending to straighten these two elements out into a straight line by pulling the feeding end of the toe downward. There is a lug 86 on the back side of the leg which limits this straightening movement to the extent shown in the solid line position of the parts in Fig. 16. The angles of the parts are such that as the leg pulls the toe radially outward away from the needles, as shown in Fig. 15, the tension spring keeps the feeding end of the toe portion against the bottom of the throat plate, thus assuring that the yarn goes over the corner of the plate. On the reverse movement, as the leg goes forward, the tension spring still keeps the feeding end of the toe in contact with the bottom of the throat till the lug 86 stops the straightening out movement just as the feeding end of the finger starts to cross the needle circle.

The invention is applicable to machines in which the clamps are horizontal, as well as to those in which the clamps are vertical. It will be obvious that the clamps and cutter could be arranged in any plane intermediate to those two planes, if so desired. Figs. 17 to 23 inclusive show various forms of the invention embodied in machines in which the clamps lie in a horizontal plane or planes. In Figs. 17 and 18 I have shown an embodiment in which there are three clamps all arranged in a single horizontal plane at one level. As in the case of the embodiment where the clamps are arranged in a vertical plane, that portion of the movement of the bight of yarn between the finger and the last needle which is due to the finger has both horizontal and vertical components. In the vertical clamp type the pushing of the yarn under the clamp is caused by the vertical component, and in the horizontal clamp by the horizontal component. In both forms or embodiments of the invention the horizontal component contacts the yarn with the clamp, but the vertical component determines the elevation at the moment of contact with the clamping devices and therefore the clamp or clamps which are to take the yarn. The vertical component may be due primarily to the yarn finger, or may be due primarily to the position of the last needle to take the yarn. This difference, in the case of the vertical movement, can be seen clearly in the vertical embodiment in Figs. 13 and 14, and the comparison in the constructions where the clamps are in horizontal planes can be seen in Figs. 18 and 20. In the case of the embodiment in Figs. 17, 18 and 19, where the selective clamping is due to both yarn and needle, it might be noted that the manipulation of the yarn can be adjusted by timing the speed at which the fingers are raised, and if desired, having it hesitate during its raising motion at the exact position where it is desired that the yarn be introduced into the clamp. In the case of such hesitation the movement of the needle will play an important part in placing the yarn under the clamp. In Figs. 17 to 19, the clamps 90, 91 and 92 are mounted on the shear plate 88 facing outwardly substantially in a radial direction but bent radially inward so

that the clamp 90 nearest the throat plate has its end nearest the needle circle, the next clamp 91 has its end further away from the needle circle, and the third clamp 92 has its end furthest of all from the needle circle. The three clamps all have their ends overlying a downwardly bevelled portion 89 on the dial or shear plate, which affords free entrance for the yarn under the clamp, the inner ends of the clamps however lying close on the flat portion of the plate 88. The dotted line yarn shown at 94 coming from the yarn finger 26 lies in the position where it has been clamped and is ready to be cut (Fig. 17). For this purpose there is a cutter 95 beyond the three clamps 90, 91, 92 lying above the yarn 94 and held in that position by a bracket 96 mounted on the shear plate 88. The cutting blade 95 is normally held up in its open position by means of a compression spring 98. The cutter can be operated by the horizontal bar 99 having a bevelled end overlying the top of the cutter 95 and adapted when pushed radially inward to depress the cutter. The arm 99 can be pushed radially inward by the same means which push in the arm 43 in Fig. 1. It will be observed in Fig. 18 that each of the yarn fingers 25, 26 and 27 are at different elevations when, owing to the raising of those yarn fingers and the movement of the last needles to take the yarns around the circle, the yarns come under the clamps. The hesitation steps on the drum cams are at different levels. As a result the yarn from finger 25 goes under clamp 90, the yarn from finger 26 goes under 91 and the yarn from finger 27 goes under 92. These three yarn positions are also shown in Fig. 17 in solid and dot-and-dash lines. It will be observed that the three yarns in Fig. 18 lie parallel when viewed from the side, but from Fig. 17 it can be seen that they lie at different angles when viewed from above.

Figs. 20 to 23, inclusive, illustrate an embodiment of my invention in which two horizontal clamps 100, 101, are arranged one above the other. As can be seen in Figs. 22 and 23, each clamp comprises a spring blade 102 and a backing plate 103 having a bevel thereon on the upper side on the corner away from the yarn finger. The manner in which this bevel assists the yarn in placing itself between the backing plate 103 and the spring blade 102 can be seen in Figs. 21 and 22. These clamps 100 and 101 are carried in a bracket 104 extending over the needle circle from the top of the latch ring on which it is mounted. There is a horizontal pair of scissor blades 105, 106 also carried by this bracket, the open ends of the blades facing radially outward. These blades are operated by lever 107 in the same manner as the lever 99 and the lever 43 of Figs. 17 and 1, respectively. In the embodiment shown in these Figs. 20 to 23, the differentiation in angle of the bights of yarn between the last needle to take it and the yarn fingers, is obtained by giving one finger a higher hesitation level than the other. While the two fingers start to rise at the same time, finger 25 hesitates at a lower level than finger 26, and because the two clamps 100 and 101 have their outer ends the same distance from the needle circle, the circular movement of the last needles to take the yarns carries the bights of yarn into different clamps. Thus the yarn from finger 26 goes above clamp 101 and into clamp 100. On the other hand, yarn finger 25 is delayed sooner, and by the time it has reached a level just below clamp 101, the last needle to take

its yarn has progressed so far around the circle as to bring its bight of yarn under the clamp 101 instead of above it. In this case there is a difference in vertical angle and a difference in horizontal angle, the geometric position of the yarns being such that in their horizontal plane the two yarns cross one above the other, just about in contact with the ends of the clamps 100 and 101. When the finger 25—or for that matter, any of the other fingers—reaches its uppermost position shown in Fig. 20, the finger will have the dotted line position of Fig. 21 and the yarn will by that time lie inside the cutting jaws as well as under a clamp, as shown in Fig. 21.

It will be observed that while the beginning of the raising of the yarn fingers may of necessity be fixed once the last needle to take any particular yarn has been determined, the rapidity with which the finger rises thereafter and whether or not it hesitates at any intermediate level or changes its rate of rise from one point of its movement to another, can be determined by proper shaping of the drum cam in accordance with the elevation or angle at which the yarn is to be presented in the clamping area.

In the mechanisms above described it will be obvious that I can clamp large yarns in one clamp and small yarns in another, or in groups of clamps, as desired. Thus, for instance, in Figs. 17 to 19 the largest yarn can be placed under clamp 92, the middle sized yarn under clamp 91 and the smallest yarn under clamp 90. In spite of the fact that the small yarn is under clamp 91 along with the middle sized yarn and both the small and middle sized yarns are under clamp 92 with the large yarn, each of the three yarns finds itself under at least one clamp where it is the largest yarn under that clamp. All this is accomplished without having any moving parts in the clamp or introducing any new parts around the throat plate.

The simplicity and effectiveness of my invention will be obvious to those skilled in the art, and many modifications which do not depart from the scope of my invention will doubtless be devised.

What I claim is:

1. In a circular knitting machine, a circle of independent needles and a plurality of yarn fingers pivotally mounted outside the circle and adapted to carry their yarns across the needle circle and up when raised from operative position, in combination with a vertical plate just inside the needle circle at a point following the fingers, and a plurality of stationary clamps on said plate adapted to hold yarns laid against the plate and raised under said clamps by the vertical movement of said yarn fingers.

2. In a circular knitting machine, a circle of independent needles and a plurality of yarn fingers pivotally mounted outside the circle and adapted to carry their yarns across the needle circle and up when raised from operative position, in combination with a plate mounted vertically just inside the needle circle at a point following the fingers with one side facing outwardly toward the needles, and a plurality of stationary clamps on the plate open ends down on the side of said plate adjacent the needles and adapted to hold yarns held against the plate when said yarns are raised by the vertical movement of the fingers.

3. In a circular knitting machine, a circle of independent needles, a vertical plate just inside the circle with one side facing outwardly toward

the needles and a plurality of downwardly depending clamps on the outer face thereof, in combination with a plurality of yarn fingers pivotally mounted outside the needle circle and adapted when raised to carry their yarn against the plate and up under the clamps.

4. In a process of clamping and cutting yarns in a circular knitting machine, the steps of allowing the last needle taking a yarn to move past a motionless, stationary, vertical clamp located inside the needle circle and then placing the yarn in the clamp by moving the yarn finger feeding said yarn so as to cause the yarn to cross the needle circle and move up under the clamp, and immediately thereafter actuating a normally open shear to cut said yarn.

5. In a circular knitting machine, a circle of independent needles, a vertical plate just inside the circle, a plurality of downwardly depending clamps on the side of said plate adjacent to the needles and a downwardly depending yarn scissors lying inside the circle when closed and across it when open, in combination with a plurality of yarn fingers pivotally mounted outside the needle circle and adapted when raised to carry their yarn against the plate and up under the clamps.

6. In a circular knitting machine, a circle of independent needles, a throat plate and a plurality of stationary clamps inside the circle whose ends are different distances from the throat plate, in combination with a plurality of yarn fingers pivotally mounted outside the needle circle and each adapted when raised to carry its yarn across the needle circle and under the clamps, and means adapted to raise the yarn fingers in varied timed relation to the position of the last needle to take the yarn whereby the yarns are controlled as to the clamps by which they are taken.

7. In a process of cutting and clamping yarns fed from outside the needle circle in a circular knitting machine, the steps of allowing the last needle to take a yarn to move past a plurality of clamps inside the needle circle, then putting in a clamp a bight of yarn between the said needle and a finger by moving the feeding end of the finger across the circle and up, and clamping another yarn under another clamp on a subsequent course by moving the finger for the second yarn in differently timed relation to the needle movement so as to present the second bight of yarn in the clamping area at a different angle.

8. In a circular knitting machine, a circle of independent needles and a plurality of yarn fingers pivotally mounted outside the needle circle and adapted when raised to carry their yarn across the circle and upwardly, in combination with a plurality of stationary vertical clamps inside the circle whose open ends are at different elevations, and means to raise the yarn fingers adapted to cause the yarns to be presented to the clamps at different angles, thereby insuring that different yarns are caught under different clamps.

9. In a circular knitting machine, a circle of independent needles, a throat plate, and a plurality of stationary clamps inside the circle whose ends are different distances from the throat plate, in combination with a plurality of yarn fingers pivotally mounted outside the needle circle and adapted when raised to carry their yarn across the needle circle and under the clamps, and means to raise the yarn fingers in a varied manner adapted to cause the yarns to be presented to the clamps at different angles, thereby in-

suring that different yarns are caught under different clamps.

10. In a circular knitting machine, a circle of independent needles, two vertical stationary clamps inside the circle one on top of the other, the lower end of the top clamp being vertically above the lower end of the under clamp, in combination with a plurality of yarn fingers pivotally mounted outside the needle circle and adapted when raised to carry their yarn across the needle circle and under the clamps, and means to raise the yarn fingers in a varied manner adapted to cause the yarn to be presented to the clamps at different angles, thereby insuring that different yarns are caught under different clamps. 15

11. In a circular knitting machine, a circle of independent needles and a plurality of yarn fingers, pivotally mounted side by side outside the needle circle and adapted when raised to carry their yarns across the needle circle and upwardly, in combination with a plurality of stationary clamps inside the circle whose open ends are at different elevations, means adapted to raise any yarn finger at the same moment relative to the last needle to take yarn when that finger is 25 to be idled, the difference in angles of the yarns due to the different distances of the yarn fingers from the clamps causing different yarns to be caught under different clamps.

12. In a circular knitting machine, a circle of independent needles and a plurality of yarn fingers pivotally mounted outside the needle circle and adapted when raised to carry their yarns across the circle and upwardly, in combination with a plurality of stationary clamps inside the circle whose open ends are at different elevations, and means adapted to raise different yarn fingers in different timed relation to the last needles to receive the yarn, whereby the bight between each last needle and its finger is presented to the clamps at a different level and goes into a different clamp or clamps. 40

13. In a circular knitting machine, a circle of independent needles, a throat plate and a plurality of stationary clamps inside the circle whose ends are different distances from the throat plate, in combination with a plurality of yarn fingers pivotally mounted outside the needle circle and each adapted when raised to carry its yarn across the needle circle against and up under the clamps, and one or more stepped cams to raise said fingers adapted to cause their fingers to hesitate in a partly raised position to insure accurate placing in the clamps. 45

14. In a circular knitting machine, a circle of independent needles, a throat plate and a plurality of stationary clamps inside the circle whose ends are different distances from the throat plate, in combination with a plurality of yarn fingers pivotally mounted outside the needle circle and each adapted when raised to carry its yarn across the needle circle against and up under the clamps, and cam means adapted to raise the yarn fingers in varied timed relation to the position of the last needle to take the yarn and to cause fingers to hesitate in a partly raised position whereby the yarns are accurately placed under different clamps. 50

15. In a circular knitting machine, a circle of independent needles, a throat plate and a plurality of yarn fingers pivotally mounted outside the needle circle and adapted to carry their yarns across the needle circle and up into a stationary yarn clamp just inside the needle circle when raised from operative position, one of said yarn 75

fingers comprising a pivoted leg, a feeding toe hinged thereto and means tending to keep said toe in contact with the throat plate, whereby said toe has forward and retracted feeding positions.

- 5 16. In a circular knitting machine, a circle of independent needles, a throat plate and a plurality of yarn fingers pivotally mounted outside the needle circle and adapted to carry their yarns across the needle circle and up into a stationary 10 yarn clamp just inside the needle circle when raised from operative position, one of said yarn fingers comprising a pivoted leg, a feeding toe hinged thereto and means tending to keep said toe to its extended length, whereby when the 15 finger is raised out of operation it assumes its extended length and guides the yarn to the clamp accurately.
17. In a circular knitting machine, a circle of independent needles, a throat plate and a plurality 20 of yarn fingers pivotally mounted outside the needle circle and adapted to carry their yarns across the needle circle and up into a stationary yarn clamp just inside the needle circle when

raised from operative position, one of said yarn fingers comprising a pivoted leg, a feeding toe hinged thereto, and means comprising a spring and stop adapted to keep the toe in contact with the throat plate in all feeding positions and to 5 permit the toe when raised out of operation to assume its extended position to guide the yarn to the clamp accurately.

18. In a circular knitting machine, a circle of independent needles and a downwardly depending clamp just inside the needle circle, in combination with a heel and toe yarn finger pivotally mounted outside the needle circle and adapted to carry the yarn across the circle up under the clamp when raised from operative position, said 15 finger having thereon means for shortening the distance between the feeding point and the pivot point of the finger when it comes into contact with the throat plate and lengthening such distance when the finger is raised out of contact 20 with the throat plate to place the yarn under the clamp.

JAMES L. GETAZ.
